INVENTOR
RALPH C. CHESNUTT

BY
Ralphmond A. Parker

ATTORNEY.

UNITED STATES PATENT OFFICE.

RALPH C. CHESNUTT, OF POTTSTOWN, PENNSYLVANIA.

MANIFOLD FOR INTERNAL-COMBUSTION ENGINES.

1,327,311.

Specification of Letters Patent. Patented Jan. 6, 1920.

Application filed April 25, 1919. Serial No. 292,651.

To all whom it may concern:

Be it known that I, RALPH C. CHESNUTT, a citizen of the United States, residing at Pottstown, county of Montgomery, State of Pennsylvania, have invented a certain new and useful Improvement in Manifolds for Internal-Combustion Engines, and declare the following to be a full, clear, and exact description of the same, such as will enable others skilled in the art to which it pertains to make and use the same, reference being had to the accompanying drawings, which form a part of this specification.

My invention relates to internal combustion engines and an object of my improvements is to provide an improved manifold and one in which the exhaust and inlet manifolds are combined.

I secure this object in the device illustrated in the accompanying drawings in which:

Figure 1 is an elevation of a manifold embodying my invention.

Fig. 2 is a plan view of the same.

Fig. 3 is a detail section on the line III—III Fig. 1 showing also the adjacent portion of the cylinder casting.

Fig. 4 is a similar section on the line IV—IV Fig. 1.

Fig. 5 is a view similar to Fig. 3 showing a modification of the construction.

Fig. 6 is a view similar to Fig. 4 except the section is continued into the cylinder casting through one of the intake passages for the engine.

a is the exhaust manifold having the discharge opening at *a*² and lateral ports *a*³ *a*³ which register with exhaust passages in the cylinder casting. *b* is a downward extension from the manifold *a* and may be cast integral therewith. The extension *b* forms a wall surrounding a groove semi-circular in cross section extending into a machined face of the manifold *a* *b*. The manifold *a* *b* has a machined face at *a*⁵ on one side adapted to fit against a machined surface on the side of the cylinder casting.

c is the cylinder casting having exhaust passages *c*² and intake passages *c*³.

*c*² is a groove semi-circular in cross section extending into the machined surface of the casting *c*. When the manifold *a* *b* is secured to the cylinder block *c* its machined face *a*⁵ comes against the machined face on said cylinder block, the lateral exhaust intake passages *a*³ in said manifold register-

ing with the discharge orifices of the passages *c*² in the cylinder casting and a groove *b*² registering with the groove *c*³ so that said grooves together form an intake manifold 60 cylindrical in cross section, half the wall of which is in the manifold and half in the cylinder casting.

*c*⁴ is a passage extending transversely across the cylinder casting, and through the 65 same, communicating at one end with the cylindrical passage or manifold *b*² *c*³ and designed to open at the other side of the cylinder casting for receiving an explosive mixture. The various intake passages *c*⁵ in the 70 cylinder casting communicate with the manifold *b*² *c*³ and are all supplied in the modification shown in Fig. 4 through the transverse passage *c*⁴.

The exhaust manifold *a* stands out a distance from the cylinder block when the manifold is secured in position and has laterally extending passages *a*⁴ *a*⁴ *a*⁴ *a*⁴ communicating with the openings *a*³ *a*³ *a*³ *a*³ and registering with the exhaust passage of the 80 engine. The interior of the exhaust manifold *a* is separated from the intake manifold *b* *b*² by an integral cast wall so that the heat from the exhaust shall be communicated to the incoming charge in the intake 85 manifold *b*² *c*³.

If it is desired to use specially heavy liquid fuel or if for any other reason, a special heating of the intake gases is required the cavity of the exhaust passage *a* 90 is extended downward as shown in Fig. 5 so that the separating wall between the intake and exhaust manifold shall be of greater extent.

If it is desired to have the carburetor upon the same side of the engine as the valves and manifold said manifold is provided with a passage *c*^{4a} (Fig. 6) having its wall cast integral with the manifold *a* *b* and serving as a conduit to admit the explosive mixture 100 to the intake manifold.

The above described construction locates the exhaust passage so that, where it extends beyond the intake passage, the atmospheric air shall have access to its entire outside 105 wall.

What I claim is:

1. In an apparatus of the kind described, the combination of a cylinder block casting, a manifold, said manifold being adapted to 110 be secured to said casting, a groove in the cylinder casting, a groove in said manifold,

said grooves being adapted to register with each other and their walls together to form the walls of the intake passage, said manifold being provided with an exhaust passage having a portion of its wall in common with a portion of said intake passage, said exhaust manifold being located at a distance from the joining surface of said manifold and cylinder casting, and so that the outer side air shall have access to a large portion of its inclosing wall.

2. In an apparatus of the kind described, the combination of a cylinder block casting, a manifold, said manifold being adapted to be secured to said casting, a groove in the cylinder casting, a groove in said manifold, said grooves being adapted to register with each other and their walls together to form the wall of the intake passage, said manifold being provided with an exhaust passage having a portion of its wall in common with a portion of the wall of said intake passage, said exhaust manifold being located at a distance from the joining surfaces between

said manifold and cylinder casting, a passage transversely through said cylinder casting communicating with the groove in said cylinder casting for the purpose described.

3. In an apparatus of the kind described, the combination of a cylinder block casting, a manifold, said manifold being adapted to be secured to said casting, a groove in the cylinder casting, a groove in said manifold, said grooves being adapted to register with each other and their walls together to form the wall of the intake passage, said manifold being provided with an exhaust passage having a portion of its wall in common with a portion of the wall of said intake passage, said exhaust manifold being located at a distance from the joining surfaces between said manifold and cylinder casting and so constructed that access of air is permitted all around said manifold for a portion of the length of said manifold.

In testimony whereof I sign this specification.

RALPH C. CHESNUTT.
